UNITED STATES PATENT OFFICE.

RICHARD B. SARGENT, OF ROCK ISLAND, ILLINOIS, ASSIGNOR TO CHARLES E. SARGENT, OF ROCK ISLAND, ILLINOIS.

SEPARATOR AND VAPOORIZER ATTACHMENT FOR INTERNAL-COMBUSTION ENGINES.

Application filed May 5, 1922. Serial No. 558,660.

To all whom it may concern:

Be it known that I, RICHARD B. SARGENT, a citizen of the United States, residing at Rock Island, in the county of Rock Island 5 and State of Illinois, have invented a new and useful Separator and Vaporizer Attachment for Internal-Combustion Engines, of which the following is a specification.

It is the object of my present invention to 10 provide a simple and effective device for separating liquid particles from a gaseous stream containing them; with especial reference to such separation of particles of fuel from the mixture of fuel and air supplied 15 by a carburetor to an internal combustion engine, in combination with means for heating this separated liquid so that it will be returned into the air stream as a vapor.

My present invention is an improvement 20 on that shown in the application of Lawrence J. May, Serial No. 465,966, filed May 2, 1921, for a gasifier. It is more effective than the May device because in the latter the rotating blades which are in the path of 25 the stream of mixed air and fuel tend to travel at such a speed that many of the liquid particles in the mixture pass by without striking them, so that those liquid particles are not deflected into the heating chamber. According to my present invention, I 30 reduce the speed of the fan, so that a much larger part of the liquid particles, if not substantially all of them, strike the blades and are deflected thereby into the heating chamber. There are other features of difference 35 over the May device, as will appear herein-after.

The accompanying drawing illustrates my invention: The single figure of such drawing 40 is a vertical central section through a gasifier embodying my invention, with some of the parts of the wind wheel shown in elevation.

I have shown my invention in its preferred use, for insertion between the carburetor and the intake manifold of an internal combustion engine, with a heating chamber heated by the exhaust gases from the exhaust manifold. For this use, in the 45 arrangement shown, there is an upper fitting 10 having an outlet pipe 11 leading to the intake manifold; a lower fitting 12 arranged at its lower end to be connected to the carburetor to receive the stream of mixed air 50 and fuel therefrom; and an intermediate

section 13 provided with an inner annular chamber 14 and an outer heating annular chamber 15, the latter being connected in the path of the exhaust gases from the exhaust manifold to the atmosphere so that such exhaust gases heat the chamber 14. The intermediate section 13 is placed between the upper and lower sections 10 and 12, with suitable heat-insulating bushings 16 at the joints to keep the upper and lower sections 60 comparatively cool. The three sections are fastened together by a single central vertical bolt 17 which carries nuts 18 bearing on suitable abutments provided on the sections 10 and 12, preferably with suitable self-adjusting washers interposed between such abutments and the nuts. The bolt 17 lies at about the middle of the vertical passageway extending from the fitting 12 through the intermediate section 13 into the fitting 70 10; and the chambers 14 and 15 surround this vertical passageway.

A tube 20 is carried between bolts 17 for rotation thereon. This tube supports a number of projecting blades 21, which form a 80 wind wheel arranged in a horizontal plane (in the arrangement shown) in the plane of an opening 22 from the chamber 14, into the central passageway. Each of these blades has three sections—an intermediate section 35 23 which is oblique with respect to the axis of the sleeve and the direction of stream flow, a lower section 24 which is at a smaller angle or preferably at zero angle to the axis of the sleeve and the direction of stream 85 flow, and an upper section which forms a radial trough 25 opening downward. A ring 26 concentric with the sleeve 20 encircles the blades 21, and engages the outer ends 90 of such blades, to hold them in place against action of centrifugal force; for such centrifugal force is very large, because the speed of rotation due to the high speed of travel of the explosive mixture from the carburetor to the engine is high. The ring 26 has an inturned flange 27 at its upper end; and just below such flange has a series 95 of radial holes 28, which preferably are in line with the troughs 25.

In operation, the stream of mixed air and fuel which travels upward from the fitting 12 through the section 13 into the fitting 14 on its way from the carburetor to the intake manifold of the engine must pass the blades 21. The action of this stream on the oblique 105

- upper parts 23 of such blades produces rotation of the blades as a unit; but this rotation is retarded or damped, to a certain extent, by the parts 24 of less or no obliqueness.
- 5 Because of this retarding action, the blades 21 cannot rotate sufficiently rapidly to allow many particles of liquid fuel to get by the blades without striking them. The air of the stream strikes the portions 23 of the 10 blades and is deflected thereby, because of this retarded rotation of the blades, instead of passing straight through; and the fuel which strikes the blades is carried along the surface of the blades into the troughs 25, 15 and thrown outward by centrifugal force along such troughs and through the holes 28 into the chamber 14. Some of the liquid fuel travels upward along the side walls of the passageway, and along the inside of the 20 ring 26; and this wall-traveling fuel is caught by the flanges 27, so that it flows around the ring and out through the holes 28 into the chamber 14. Thus the greater part of the liquid fuel in the stream of the 25 mixture from the carburetor is thrown into the chamber 14. It collects in this chamber, which preferably has an upstanding inner wall 29 from the bottom thereof to prevent back flow of liquid from such chamber.
- 30 This liquid thus caught in the chamber 14 is heated by the exhaust gasses in the jacket 15, and is vaporized by the heat; and the fuel vapors escape from the chamber 14 through the opening 22 thereof, and remix 35 with the air stream passing through the intake manifold.
- I claim as my invention:
1. In combination, a conduit for carrying a mixture of liquid and gas, a wind-wheel 40 rotatably mounted in said conduit and having outwardly projecting blades, said blades being partly oblique and partly parallel to the direction of stream-flow, a chamber opening into said conduit in position to have liquid from said blades thrown outwardly into it, and a ring encircling said blades and reinforcing them against centrifugal force.
  2. In combination, a conduit for carrying a mixture of liquid and gas, a wind-wheel 45 rotatably mounted in said conduit and having outwardly projecting blades mounted on a common hub, said blades having parts at different angles to the direction of stream flow and being provided with troughs opening against the stream flow at their edges where the stream leaves the blades, and a chamber opening into said conduit in position to have liquid from said blades thrown outwardly into it.
  3. In combination, a conduit for carrying a mixture of liquid and gas, a wind-wheel 50 rotatably mounted in said conduit and having outwardly projecting blades, said blades having parts at different angles to the direction of stream flow and being provided with
- troughs opening against the stream flow at their edges where the stream leaves the blades, a chamber opening into said conduit in position to have liquid from said blades thrown outwardly into it, and a ring encircling said blades to hold them against centrifugal force, said ring being provided with openings through which said troughs may discharge outwardly. 70
4. In combination, a conduit for carrying a mixture of liquid and gas, a wind-wheel rotatably mounted in said conduit and having outwardly projecting blades, said blades being partly oblique and partly parallel to the direction of stream-flow, a chamber opening into said conduit in position to have liquid from said blades thrown outwardly into it, and a ring encircling said blades and reinforcing them against centrifugal force, said ring having an inturned flange at the edge where the stream leaves the ring and being provided with outward openings through it in position to discharge into said chamber. 75
5. In combination, a conduit for carrying a mixture of liquid and gas, a wind-wheel rotatably mounted in said conduit and having outwardly projecting blades, said blades having parts at different angles to the direction of stream flow and being provided with troughs opening against the stream flow at their edges where the stream leaves the blades, a chamber opening into said conduit in position to have liquid from said blades thrown outwardly into it, and a ring encircling said blades to hold them against centrifugal force, said ring having an inturned flange at the edge where the stream leaves the ring and being provided with outward openings through it in position to discharge into said chamber. 80
6. In combination, a conduit for carrying a mixture of liquid and gas, a wind-wheel rotatably mounted in said conduit and having outwardly projecting blades, a chamber opening into said conduit in position to have liquid from said blades thrown outwardly into it, and a ring encircling said blades and reinforcing them against centrifugal force, said ring having an inturned flange at the edge where the stream leaves the ring and being provided with outward openings through it in position to discharge into said chamber. 85
7. In combination, a conduit for carrying a mixture of liquid and gas, a wind-wheel rotatably mounted in said conduit and having outwardly projecting blades, said blades having oblique portions for causing the rotation of the wind-wheel by the flow of the stream and also having troughs opening against the stream flow at the blade edges where the stream leaves the blades, said wind wheel also having damping parts for reducing its speed of rotation, and a chamber 90

- ber opening into said conduit in position to have a liquid from said blades thrown outwardly into it.
8. In combination, a vertical conduit for carrying a mixture of liquid and gas, a wind-wheel mounted on a vertical axis in said conduit and having outwardly projecting blades, and a chamber surrounding said conduit and opening into said conduit in the plane of said blades, said blades having oblique parts and also having troughs which open rearwardly and are located on the blade edges where the stream leaves the blades and also having damping parts for acting on the stream to oppose the rotation of the wind-wheel.
9. In combination, a conduit for carrying an explosive mixture from a carbureter to an internal combustion engine, a wind-wheel arranged in said conduit and having outwardly projecting blades, and a chamber surrounding said conduit and opening into the conduit in the plane of said blades, said blades being provided with oblique portions for causing rotation of the wind-wheel and with other portions for retarding such rotation and with troughs opening against the direction of stream flow for catching the fuel which strikes the blades and discharging it into said chamber.
10. In combination, a conduit for carrying an explosive mixture from a carbureter to an internal combustion engine, a wind-wheel arranged in said conduit and having outwardly projecting blades, a chamber surrounding said conduit and opening into the conduit in the plane of said blades, said blades being provided with oblique portions for causing rotation of the wind-wheel and with other portions for retarding such rotation and with troughs opening against the direction of stream flow for catching the fuel which strikes the blades and discharging it into said chamber, and means for heating said chamber by the exhaust gases from the engine.

In witness whereof, I, RICHARD B. SARGENT have hereunto set my hand at Champaign, Illinois, this 1st day of May, A. D. one thousand nine hundred and twenty-two.

RICHARD B. SARGENT.
